UNITED STATES PATENT OFFICE

131,163

DESIGN FOR A RETINOSCOPE OR THE LIKE

William F. Peck, Snyder, Albin A. Gradisar, Buffalo, and John T. Armbruster, Niagara Falls, N. Y., assignors to American Optical Company, Southbridge, Mass., a voluntary association of Massachusetts

Application September 10, 1941, Serial No. 103,271

Term of patent 14 years

To all whom it may concern:

Be it known that we, William F. Peck, Albin A. Gradisar, and John T. Armbruster, citizens of the United States, residing at Snyder, Buffalo, and Niagara Falls, in the counties of Erie, Erie, and Niagara, respectively, and State of New York, have invented a new, original, and ornamental Design for a Retinoscope or the like, of which the following is a specification, reference being made to the accompanying drawing, forming a part thereof.

Fig. I is a rear elevational view of a retinoscope or the like, embodying the new design;

Fig. II is a side elevational view with part of

the handle broken away for convenience of illustration.

Fig. III is a front elevational view with part of the handle broken away for convenience of illustration.

The characteristic features of the design reside in the portions shown in full lines in the drawing.

What is claimed is:

The ornamental design for a retinoscope or the like, substantially as shown and described.

WILLIAM F. PECK.

ALBIN A. GRADISAR.

JOHN T. ARMBRUSTER.
